STEAM IRON AND FILLING DEVICE

Albert C. Hoecker, St. Louis, Mo.

Application March 31, 1948, Serial No. 18,090

2 Claims. (Cl. 38—77)

This invention relates to improvements in steam irons and more specifically to steam irons which can be kept in constant operation without interfering with the normal steaming operation of the iron.

The primary object of the invention is to provide a steam iron with means for injecting water into the boiler of the iron.

Other and further objects will appear in the specification and be specifically pointed out in the appended claims, reference being had to the accompanying drawings exemplifying the invention and in which:

Fig. 1 is a rear view of the iron and partly broken away showing the improved pumping mechanism attached to the iron.

Fig. 2 is a vertical view of the pump detached from the iron.

Fig. 3 is a vertical central sectional view of the pump and valve.

Fig. 4 is a view of the valve and fragmentary part of the pump.

Fig. 5 is a side view of the iron and top view of the valve.

Referring by numerals to the accompanying drawings, 1 designates the iron generally, and screwed or otherwise secured in the upper wall 13 of the boiler of the iron is a shell or plug 122 having a tapered opening 123 which communicates with the interior of the boiler, and rotatably mounted in the opening 123 is a correspondingly tapered valve 125 having projecting members 128 for rotating the valve. The valve 125 is provided with a longitudinal central opening which also communicates with the interior of the boiler and acts as a passageway for the admission of water into the boiler. The central opening or passage-way in the lower portion of the valve 125 is enlarged as indicated at 129, so as to provide a valve seat for the ball valve 132. The upper portion 131 of the valve extends above the ball valve 132 and the central opening 130 is adapted for the reception of the nozzle 137 to form a connection between the valve and the pump 136. A plug 134 having a central opening 135 communicating with the opening 129 in the valve 125 is screw-threaded in the lower end of the valve and interposed and engaging the ball valve 132 and plug 134 is a compression spring 133 for holding the valve in normal position on its seat. The lower part of the plug 134 engages the lower part of the shell or plug 122 for holding the valve 125 in rotatable position in the shell or plug 122. Extending through the wall of the shell or plug 122 and communicating with the opening 129 below the ball valve 132 is a water outlet 124 which registers with a water outlet 126 in the valve and both of said outlets extend above the boiler wall 13, so as to provide a water outlet for the water that may remain in the boiler after the ironing is completed. Obviously, the outlets 124 and 126 must register or be in alignment when the boiler is being emptied of water, and closed when the iron is in operation. To accomplish the desired result the shell or plug 122 is provided with a slot 127 which cooperates with a pin 127' in

2

the side of the valve 125 to provide a stop for the valve 125, when in closed, or open position.

The pump for filling the boiler consists of a cylinder 136, closed at both ends, the upper end being closed by a 5 removable head or cap 92, and in the cylinder 136 is a cup-shaped piston 87 secured to a piston rod 88 by washers 89 and nuts 90, said rod extending through an opening 91 in the cylinder head 92 and the upper end of the rod 88 is provided with a knob 93 for operating the piston. The 10 lower end of the cylinder is provided with a nozzle 137 which communicates with the interior of the cylinder, and slidably mounted on the nozzle 137 is a cup-shaped member 138, having a cup-shaped rubber member 139 mounted therein, and interposed between the cylinder 136 and the 15 cup-shaped member 138 is a spring 140. It will be noted that the spring 140 holds the cup-shaped rubber washer 139 against the upper portion 131 of the valve 125 thereby sealing the opening 130 around the nozzle 137, when the nozzle is inserted in the opening 130, when filling the 20 boiler with water. The cup-shaped members 138 and 139 are prevented from coming off the nozzle 137 by the friction of the rubber cup-shaped member 139 on the nozzle.

To operate the pump and with the pump detached from the valve 125 the nozzle 137 of the cylinder 136 is inserted 25 in a container filled with water and the knob 93 pulled outwardly until the piston 87 reaches the top end of the cylinder 136, this will create a vacuum in the cylinder 136 thereby filling the cylinder with water. When the cylinder is filled with water, the nozzle 137 is inserted 30 in the opening 130, in the valve 125, as shown in Fig. 1, the knob 93 is then forced downwardly causing the cylinder also to be forced downwardly and causing the cup-shaped rubber member 139 on the nozzle 137 to engage the part 131, further downward movement of the cylinder 35 will cause the tension of the spring 140 to increase and force the rubber cup-shaped member against the part 131 on the valve 125, sealing the opening around the nozzle 137 against water leakage. Further downward movement of the piston 87 and cylinder 136 will cause 40 the nozzle 137 to engage the ball valve 132, forcing the ball off its seat, causing the water within the cylinder 136 to flow through the slots 141 in the lower end of the nozzle 137 and around the ball valve 132 and through the opening 135 in the plug 134 into the boiler.

After the boiler is filled the pump cylinder 136 including 45 the nozzle 137, spring 140, cup-shaped members 138 and 139 are detached from the boiler. To remove or detach the pumping mechanism from the boiler it is only necessary to grasp the cylinder 136 and lift the cylinder upwardly thereby pulling the nozzle 137 out of the opening 130 in the upper portion 131 of the valve 125, leaving the iron with a streamlined surface.

To empty the boiler of any water that may remain in the boiler after the ironing is completed, it is only necessary to rotate the valve 125 by the projecting members 50 128 until the openings 124 and 126 are in alignment, as shown in Fig. 3. When the valve 125 is in the position shown in Fig. 3 the iron is turned on its side causing the water in the boiler to flow through the opening 134 and out 55 the openings 124 and 126. After the water is out of the boiler, the valve 125 is rotated until the valve is in the position shown in Fig. 4 closing the outlet 126.

While I have illustrated what I believe to be preferred embodiments of my invention, it is obvious other modifications may be made without departing from the spirit thereof, and therefore the exact forms shown are to be taken as illustrative only, and not in a limiting sense.

What I claim is:

1. The combination of a steam iron having a steam 60 boiler, and a filler device, said device comprising a valve casing attached to said boiler and having a valve seat and an opening for the introduction of water into said boiler,

a valve in said casing and held against said seat by a spring, a detachable pump having a nozzle to be inserted in said opening to force the valve off said seat, and means for forcing the water in said pump past said valve into said boiler.

2. The combination of a steam iron having a steam boiler, and a filler device, a valve casing in said boiler, a check valve casing rotatably located in said first mentioned casing, a passageway in said check valve casing, a valve seated in the lower end of said passageway, means for holding said valve in seated position, a passageway through each of said casings on the side of said casings and extending above said boiler and beneath said passageway valve, so that the water in the boiler can be drained through said last mentioned passageways when the ironing is completed, and means on said check valve casing for moving said last mentioned passageways in and out of registration, a pump cylinder having nozzle at one end through which water is drawn into said cylinder, a piston in said cylinder having a rod secured thereto for forcing the water out of said cylinder, means on said rod for manually operating said piston, said nozzle slidably connected to said first mentioned passageway to form a connection between said pump and said boiler for directing the water from said pump into said boiler and so said

4
pump can be quickly detached from said boiler after water from said pump has been injected into said boiler.
